DOOR CHECK AND CLOSER

Frank M. Newell, Lowell, Mich.

Application August 17, 1939, Serial No. 290,697

2 Claims. (Cl. 16—70)

This invention relates to improvements in door checks and closers and pertains particularly to an air check wherein novel and improved features of construction are employed.

5 The present invention has for its primary object to provide a door closer and check employing a piston and cylinder check unit and a coupling means between the piston and the door frame which is so designed as to facilitate the 10 opening of the door on which the device is mounted to a greater degree than is possible with similarly designed devices.

Another object of the invention is to provide in a device of the character described, a novel 15 piston cylinder construction which is so designed that it may be constructed of light weight material and assembled in such manner that the cost of production will be materially less than the cost of producing similar cylinders where the body of 20 the cylinder is formed of cast material and the ends are secured to the cylinder by screw threads or other means involving costly construction operations.

Still another object of the invention is to provide in a door check and closer a novel means 25 for securing the piston cylinder to the body of the door whereby it will be firmly held in position thereon.

A still further object of the invention is to provide in a device of the character set forth, a novel 30 form of coupling link between the piston rod and the door frame whereby the door is permitted to open to its fullest extent.

The invention will be best understood from a 35 consideration of the following detailed description taken in connection with the accompanying drawing forming part of this specification, with the understanding, however, that the invention is not to be confined to any strict conformity with the showing of the drawing but may be changed 40 or modified so long as such changes or modifications mark no material departure from the salient features of the invention as expressed in the appended claims.

45 In the drawing:

Fig. 1 is a view in elevation of the device embodying the present invention, showing the same applied.

50 Fig. 2 is a top plan view of the device showing the cylinder in longitudinal section.

Fig. 3 is a view of one of the cylinder clamping rings.

55 Fig. 4 is a sectional view on the line 4—4 of Fig. 2.

Fig. 5 is a view illustrating a modification of the link supporting bracket.

Referring now more particularly to the drawing, the numeral 1 generally indicates a portion of a door frame in which is mounted a door 2 which may be a screen door or similar type of door upon which checks and closers are employed. The present check and closer device is designed particularly to be used upon doors which swing outwardly, such as screen doors or the like, the check and closer being mounted upon the inner side of the door and connecting the same with the inside of the door frame.

The present device comprises a piston cylinder 3 which in accordance with the present invention is formed of a suitable light weight sheet metal such as tin, being rolled upon a suitable mandrel and suitably seamed longitudinally to form the cylinder barrel. One end of the cylinder barrel is closed by a metal cap 4 which is secured to the end of the barrel in a suitable manner while the other or rear end of the cylinder barrel is closed by the wood plug 5 the metal of the barrel being secured to the plug by crimping the end of the barrel into the encircling 25 channel 6 which is formed in the plug.

In the head or front end of the cylinder, the cap 4 is suitably apertured to receive a screw 7 which upon its inner end carries within the cylinder the metal head 8 between which and the cap 4 is a rubber valve body 9. The aperture through which the screw passes is relatively large as compared to the screw diameter and the metal of the head 8 as radial grooves 10 pressed 30 therein which extend beyond the rubber valve 9 as illustrated. Upon the outer end of the screw 35 7 is a nut 11 which, when it is tightened up on the screw against the head 8, compresses the rubber body 9 so as to partially close the air grooves 10 leading to the opening through which the 40 screw passes.

The closure plug 5 at the inner end of the cylinder barrel is centrally apertured to receive the stem 12 of a piston 13 which snugly fits within the barrel and surrounding this stem and interposed between the piston 13 and the plug 5 is an expansion spring 14 which normally urges the piston toward the front end of the barrel. The end of the stem 12 at the rear end of the piston cylinder is turned to form the lateral hinge finger 15.

The numeral 16 indicates a coupling link which connects the piston stem finger 15 with the door frame 1 when the check and closer device is mounted in operative position. This link is pref- 55

erably in the form of a flat bar which through the major portion of its length is of arcuate form, as indicated at 17, and the remaining or minor portion of the link length is oppositely directed to the portion 17, as indicated at 18. The link thus takes the form roughly of an ogee curve wherein one of the two curved portions is of greater length and is struck on a greater radius than the other portion. The free end of the portion 17 of the link which is the portion of greatest curvature is apertured, as indicated at 19, to receive the hinge finger 15 of the piston stem, and the concave side of this curved portion is directed toward the door body 2 on which the piston cylinder is mounted. The shorter curved end portion 18 has its convex side directed toward the door and is pivotally attached to the frame 1 by a supporting bracket 20. This particular bracket 20 is shown as having a substantially U-shaped form in cross-section so as to provide the two spaced side ears 21 between which the inner end of the link is pivotally connected by means of the pivot pin 22. The yoke portion of the bracket 20 is attached by a screw 23 or in any other suitable manner to the door frame at the side of the same, of course, to which the door 2 is hinged. While the bracket indicated by the numeral 20 is the form preferred for attaching the coupling link to the door frame, there may be employed an angle bracket of the type shown in Fig. 5 and indicated generally by the numeral 24, in which case the horizontally disposed portion of the angle which is indicated at 25, would carry the pivot rivet 26 to which the short curved end of the link 16 is attached.

The piston cylinder 3, as previously stated, is firmly secured to the inner side of the door by means of the bracket clamps 27. As shown, each of these clamps is formed of a single piece 40 of metal which is shaped about the barrel of the piston cylinder to form the ring 28, and one end of the clamp extending tangentially from the ring to form the terminal 29 while the other end is reversely bent to form the second terminal 30, which terminals are brought into superposed relation to have mounting screws 31 passed through apertures formed therein. Thus it will be seen that as the terminal portions of the clamp rings are drawn together and against the body of the door, the ring 28 will be closed about the piston cylinder so as to firmly clamp the same and hold it against movement. While other types of clamps might be employed, this specific type is preferred in view of the ease with which the double function of clamping the cylinder and firmly securing it to the wall may be accomplished.

From the foregoing, it will be readily understood that the present device is mounted in a horizontal plane against the inner side of the door 2 and that the piston cylinder is firmly held against movement with respect to the door, the only pivotally supported element being the coupling link 16 between the stem 12 of the piston and the bracket 20 which is mounted on the door frame. By reason of the peculiar form of the link 16, it will be readily apparent that the door

2 may be swung through a greater arc than is possible with other types of checks and closers where there are employed straight coupling links between the check piston and the door frame or where the piston stem of the check is directly pivotally coupled to a bracket on the frame. With such constructions it is only possible to swing the door through approximately 90° whereas with the present device it is possible to swing the door back substantially to a position where its outer side will be parallel with the wall in which the door frame is mounted.

While the device has been illustrated and described as having a spring member in the cylinder for forcing the piston in a direction which will effect the closing of the door to which the device is attached, it will be understood that the device may be used solely as a check if desired, by leaving out the spring as in some instances screen doors are provided with spring operated hinges by which they are forced into closed position, therefore, the device, when the spring 14 has been left out, may be employed as a check.

What is claimed is:

1. A door check and closer, comprising a piston cylinder, a piston within the cylinder and having a stem extending through an end of the cylinder, means for securing said cylinder against movement to the body of a door, a bracket adapted to be connected with the door frame adjacent the hinged side of the door, a rigid link having an end pivotally attached to said bracket and having its other end pivotally connected with said piston stem, said link being of longitudinally arcuate form throughout the major extent of its length and then extending straight through the remaining portion to one end and disposed with respect to the door carrying the piston cylinder with the concave side directed toward the door, resilient means urging the movement of the piston to draw the stem into the cylinder, and means for bleeding air from the cylinder between the end of the link and the piston.

2. A door check and closer, comprising a piston cylinder, a piston slidable in the cylinder and carrying a stem extending through an end of the cylinder, spring means in the cylinder urging the piston to move toward one end to draw the stem into the cylinder, air bleeding means in the said one end of the cylinder, a rigid link member comprising a bar having a major portion thereof longitudinally curved and the remaining portion reversely bent to extend straight to the end, the end of the major portion being pivotally attached to said piston stem, a bracket for attachment to the inner side of a door frame and having the end of the reversely bent straight portion pivotally attached thereto, the said pivots being parallel and vertically disposed when the check is in operation and the concave side of the major curved portion being directed toward the door on which the cylinder is mounted, said straight portion being substantially parallel with the said inner side of the frame when the door is swung open through an arc of 180°, and means for securing the cylinder to said door.

FRANK M. NEWELL.
